LEOPOLD NATHAN, OF ZURICH, SWITZERLAND.

APPARATUS FOR CLEANING CARBONIC ACID.

1,268,872.

Specification of Letters Patent. Patented June 11, 1918.

Application filed January 11, 1918. Serial No. 71,481.

To all whom it may concern:

Be it known that I, LEOPOLD NATHAN, a subject of the Emperor of Germany, residing at Zurich, Switzerland, have invented certain new and useful Improvements in an Apparatus for Cleaning Carbonic Acid in the Art of Brewing Beer, of which the following is a specification.

In the method of brewing beer with the apparatus herein disclosed, the carbonic acid generated is cleaned before it is again used in the chain of processes. This is done among other things for the purpose of removing what is known as fresh bouquets which consist principally of a number of ethers, the exact character of which is not yet accurately known.

If this cleaning is done in the usual way, a number of difficulties are encountered. Long continued experiments have shown that many if not all of these difficulties are done away with by the process and apparatus now to be described and that such process results in a complete and economical removal of all impurities found in the carbonic acid. The process consists essentially in the successive passing of the carbonic acid through water, permanganate of potash and sulfuric acid, whereby with small amounts of washing materials and large amounts of gases, large contact surfaces and long periods of contact are obtained. Provision is made for drying the carbonic acid by retaining any traces of the washing fluid which may be carried along, as well as for the quick removal and replacing of the washing fluid, after it has been utilized and become useless.

As compared with the known processes (Brewer and Maltster, pages 216-220, und Zeitschrift fuer die gesamte Kaefteindustrie, 1904, page 7, column 1, §2), in the present process the sequence of the several cleaning means and operations (water, permanganate, drying, concentrated sulfuric acid and alkali) is of great importance on account of the peculiar nature of the substance having the odors and tastes previously referred to and which are to be removed. The fact that sulfuric acid is used after the permanganate, and not vice versa, is of great importance, as is also the drying before the treatment by sulfuric acid, as only thus can the concentration of the sulfuric acid be maintained.

Furthermore, the apparatus used in my

herein described process embodies important and novel characteristics. Both process and apparatus will be best understood by the aid of the following description and of the accompanying drawing which shows a central longitudinal section through the apparatus.

The carbonic acid first passes into the vessel A, containing water, by means of the pipe a, which opens into the top of the bell b, and then through small slots or notches a' formed in the lower edge of the bell, whereby the gas, as it passes around the edge out of the bell, is broken up into small bubbles, into the space c which also contains water. Here the gas bubbles rise along the outer wall of the bell and are caught under the roof-shaped annular projections or flanges d, which are provided with numerous small holes. As the gases pass through these holes, they are again broken up so that an intimate and continuous contact with the water is obtained until the gas escapes through pipe e.

By use of the bell b the water will not be forced into the feed pipe a, but will accumulate in the annular space surrounding the bell, if pressure difference or back pressure occurs.

From the water container A the carbonic acid flows through the pipe f into the vessel B with its bell similar to the bell in A, in which a solution of permanganate of potash is contained, and is again washed. As a result of these two washings most of the impurities are removed from the carbonic acid, but some of the impurities can only be destroyed by the aid of concentrated sulfuric acid.

Before the gas is passed through the sulfuric acid, the gas must be dried, however, in order to prevent a rapid deconcentration of the sulfuric acid. For this purpose a water separator C, of any usual construction, is inserted into the path g of the carbonic acid as it flows from B to the drying tower D. This drying tower is filled with any suitable liquid absorbing substance, through which the carbonic acid rises after it has been finely broken up by means of a sieve h at the bottom of the tower. A special arrangement is provided for regenerating this water tower from time to time by driving out the water retained by the liquid absorbing substance. For this purpose an electric gas heater L is provided. By shutting off the pipe g and opening faucet k a current

of carbonic acid may be sent through and heated in the said gas heater and from thence sent through the drying tower D. The heated gas after it has left the drying tower, 5 may be cooled and thereby freed from the H_2O taken up by it.

The dried carbonic acid after having passed through the vessels A, B and C flows through the pipe k into the sulfuric acid 10 container E, of the same general construction as the vessels A and B except that a pipe m is provided for the purpose of filling and emptying the vessel and of taking out of samples. At the upper part of the bell, 15 a layer of clay balls is inserted which will retain any sulfuric acid bubbles which the flowing gas may have carried with it. The carbonic acid, which is not yet completely freed from all impurities, flows through the pipe n into the bottom of the vessel F, where any traces of sulfuric acid which have been 20 carried along are removed. For this purpose a sieve μ , similar to the sieve ν , is provided at the bottom of the vessel for the 25 purpose of breaking up the gases and the space above the sieve is provided with a quantity of pumice stone and crystallized soda; or the vessel may contain a solution of soda instead.

30 The vessels are so connected with each other that during the process of operation any one of them may be cut off from the others in order to empty and refill the same with fresh liquids, or for any other desired 35 purpose. To accomplish this, three-way cocks are provided in the several connecting pipes.

Various modifications may be made with-

in the spirit of my invention. Thus the gas heater L may be equivalent by any other 40 form of heater or mode of heating. Similarly, instead of any one or more of the individual devices A, B, etc., a plurality of such devices may be employed.

Having described my invention, I claim— 45

1. In a gas purifying apparatus, the combination of a vessel adapted to contain a washing medium, an open-bottomed bell concentrically disposed within said vessel the free space within the bell being at least as 50 great as that outside of the bell, and a feed pipe for the gas to be purified, said bell having a downwardly and outwardly extending peripheral flange for breaking up the bubbles of gas fed to the bell. 55

2. In a gas purifying apparatus, the combination of a vessel adapted to contain a washing medium, an open-bottomed bell concentrically disposed within said vessel, the free space within the bell being at least as great 60 as that outside of the bell, and a feed pipe for the gas to be purified, said bell having a plurality of peripheral flanges extending downwardly and outwardly nearly to the wall of the surrounding vessel and provided with 65 concentric rows of perforations for breaking up the bubbles of gas fed to the bell, the bottom of the bell being notched for the same purpose.

In testimony whereof, I have hereunto set 70 my hand.

LEOPOLD NATHAN.
